UNITED STATES PATENT OFFICE.

CLARENCE HEISEY, OF NEWARK, OHIO, ASSIGNOR TO A. H. HEISEY & CO., OF NEWARK, OHIO.

DESIGN FOR A SUGAR-TRAY OR SIMILAR RECEPTACLE.

45,138.

Specification for Design.

Patented Jan. 6, 1914.

Application filed October 29, 1913. Serial No. 798,150. Term of patent 14 years.

To all whom it may concern:

Be it known that I, CLARENCE HEISEY, a citizen of the United States, residing at Newark, Ohio, have invented a new, original, and ornamental Design for a Sugar-Tray or Similar Receptacle, of which the following is a specification, reference being had to the accompanying drawing, forming part thereof.

Figure 1 is a top plan of a sugar tray or the like embodying my design; Fig. 2 is a

side elevation; and Fig. 3 is an end elevation of the same.

I claim:

The ornamental design for a sugar tray or similar receptacle, substantially as shown.

CLARENCE HEISEY.
